NECKTIE HOLDER

Edward B. Blameuser, Niles Center, Ill.

Application January 24, 1938, Serial No. 186,498

2 Claims. (Cl. 211—100)

The invention relates to a holder for neckties and has more particular reference to an improved necktie holder of ample capacity which will require very little space and which can be 5 manufactured economically and in large quantities.

Another object of the invention resides in an improved holder for neckties and the like which may be pivotally supported from a wall, door 10 or other support so as to be movable from a normal vertical position to an approximately horizontal position for removing the necktie therefrom.

An important feature of the present holder is 15 the ease with which the ties can be removed therefrom when the holder is horizontally positioned although when hanging in its normal vertical position the ties are held on their individual retaining member in a manner so that 20 they can not accidentally fall to the floor. This automatic retaining of the ties in the holder when positioned vertically is partly due to the weight of the ties above and partly to contact with the adjacent ties or adjacent supporting 25 members as the case may be.

A further object of the present invention is 30 to provide a tie holder which will render visible a small portion only of the ties with the exception of the ties positioned to the front. Accordingly, the ties to the rear are shielded from light and do not fade as fast as would otherwise be the case. However, since a portion of each tie 35 on the holder is visible at all times, the wearer can make his selection and then lift the holder horizontally to remove the selected tie.

With these and various other objects in view, the invention may consist of certain novel features of construction and operation, as will be 40 more fully described and particularly pointed out in the specification, drawing and claims appended hereto.

In the drawing which illustrates an embodiment of the invention and wherein like reference characters are used to designate like parts—

45 Figure 1 is a perspective view showing the improved tie holder of the invention with several neckties in position thereon;

Figure 2 is a front elevational view of the present holder shown in its normal vertically hanging position; and

50 Figure 3 is a perspective view of an individual tie supporting member.

Referring to the drawing, the present necktie holder, as shown in Figure 1, is pivotally supported from a door, wall or other support 10 by

means of the journal plate 12, which provides a journal or bearing 14 for the wire frame designated in its entirety by numeral 16. The journal plate is suitably secured to the wall or door by the screw 18 and accordingly said member 5 provides a fixed support to which is pivotally secured the wire frame 16. The ends of the wire frame are bent at 20, Figure 2, and said bent ends are inserted within the bearing 14. The pivotal mounting of the wire frame 16 makes 10 possible movement of said wire frame from a normal vertical position to an approximately horizontal position, as shown in perspective in Figure 1.

Said frame is preferably constructed of a continuous piece of wire or other suitable material, the respective ends of the same being bent at 20 for reasons as above described. At the other end the wire frame is bent to form a handle portion 22, which portion may be readily 20 grasped for the purpose of lifting the holder to locate it in approximately horizontal position for the purpose of removing a tie therefrom. Mounted on the wire frame 16, so as to have movement longitudinally of said frame, are a plurality of 25 transverse members 24 on which the neckties are supported. As better shown in Figure 3, each member is provided with an elongated or oblong opening 26 through which the wire frame 16 is inserted. Also each member on its upper edge is 30 recessed at 28 and 30, the said recesses being symmetrical with respect to the centrally disposed oblong opening 26.

In order to place neckties on the holder or for 35 the purpose of removing a necktie therefrom the device is lifted by the handle portion 22 to an approximately horizontal position, whereby the necktie supporting members 24 can be readily separated since they will slide freely along the length of the wire frame. Neckties are placed 40 on the members 24, the recesses 28 and 30 being provided for the purpose. It will be observed that each member may support two neckties and since the wire frame may hold a large 45 number of said members, the capacity of the present necktie holder will be ample for all purposes, although the same will not take up very much space and in its normal vertical hanging position will be out of the way and may therefore be placed in a closet or the like where space 50 is limited.

An important feature of the present necktie holder resides in the fact that a portion of each necktie supported by the holder is visible when the holder is in its normal vertical hanging posi- 55

tion. This will be clear from reference to Figure 2, wherein it will be seen that the front neckties, namely, 31 and 32, are entirely visible, whereas, as regards the neckties to the rear, only that portion passing over the support 24 is visible. However, this is sufficient to enable a person to make a selection and then the selected necktie can be readily removed from the holder by lifting the same to an approximately horizontal position. The neckties are also prevented from accidentally slipping off their support 24 while the holder is hanging in its normal vertical position. This results by reason of the contact of the neckties with each other and also from the fact that the neckties above apply a certain weight to those below, which is further increased by the weight of the supporting members 24. This automatic retaining of the ties on the holder when positioned vertically can also be attributed in part to the sharp bend of the tie in passing over the upper edge of its supporting member 24.

As best illustrated in Figure 2, the ties on the respective sides of the present holder are in substantial alignment. In other words, the ties are positioned in back of each other and therefore the ties to the rear are shielded from light and they do not fade as fast as would otherwise be the case.

The handle portion 22, which, in the modification illustrated, is integral with the wire frame 16, additionally provides a stop for the transverse members 24. In other words, when the holder is in vertically hanging position, as shown in Figure 2, the weight of the transverse members is taken by the handle portion. It will be observed that the lowermost member is in direct contact with the flat section of the handle portion. The other transverse members are superposed thereon and the weight of these members in addition to any neckties supported thereby will be transmitted to the handle portion.

The invention is not to be limited to or by de-

tails of construction of the particular embodiment thereof illustrated by the drawing, as various other forms of the device will of course be apparent to those skilled in the art without departing from the spirit of the invention or the scope of the claims.

What is claimed is:

1. In a necktie holder, in combination, an elongated wire frame having a handle portion on one end thereof, a base providing journalling means for the other end of said frame which is pivotally supported thereby, a plurality of tie supporting members disposed transversely of the frame and extending a distance on each side of the frame for supporting a tie thereon, each member having an opening therein whereby the members are mounted on said frame in a manner to permit slidable movement, and said handle portion extending laterally beyond the frame to provide bearing portions for supporting the tie supporting members when the frame depends vertically from said base.

2. In a necktie holder, in combination, an elongated wire frame having a handle portion formed integral therewith at one end, a base providing journalling means for the other end of said frame whereby said frame is pivotally supported by said base, a plurality of tie supporting members disposed transversely of the frame and extending a distance on each side thereof, the upper edge of each member on the respective sides of the frame having a recess formed therein for receiving a tie, and each member having an opening therein whereby the member is mounted on the frame in a manner permitting slidable movement, said handle portion extending laterally beyond the frame to provide bearing portions for supporting the tie supporting members when the frame depends vertically downward from said base.

EDWARD B. BLAMEUSER.
